United States Patent Office

Des. 199,062
Patented Sept. 8, 1964

199,062

SWITCHPLATE

Alex Martin, Southfield, Montgomery Ferar, Huntington Woods, and Carl W. Sundberg, Bloomfield Hills, Mich., assignors to The International Nickel Company, Inc., New York, N.Y., a corporation of Delaware

Filed Jan. 6, 1964, Ser. No. 78,091

Term of patent 14 years

(Cl. D26—13)

FIG. 1 is a front elevational view of a switchplate showing our new design.

FIG. 2 is a side view of the switchplate.

FIG. 3 is a top edge view of the switchplate.

We claim:

The ornamental design for a switchplate, as shown.
